UNITED STATES PATENT OFFICE.

WILLIAM W. DEAN, OF CHICAGO, ILLINOIS, ASSIGNOR TO THE KELLOGG SWITCH BOARD AND SUPPLY COMPANY, OF SAME PLACE.

PLUG AND SOCKET FOR TELEPHONE SYSTEMS.

SPECIFICATION forming part of Letters Patent No. 657,339, dated September 4, 1900.

Application filed April 28, 1899. Serial No. 714,872. (No model.)

To all whom it may concern:

Be it known that I, WILLIAM W. DEAN, a citizen of the United States, residing at Chicago, in the county of Cook and State of Illinois, have invented a certain new and useful Improvement in Plugs and Sockets for Telephone Systems, of which the following is a full, clear, concise, and exact description, reference being had to the accompanying drawings, forming a part of this specification.

My invention relates to a plug and socket for telephone systems, my object being to provide an improved form of socket or spring-jack switch for the terminals of the telephone-line, and also to provide an improved form of connecting-plug for insertion therein when it is desired to connect the telephone-lines for conversation.

I have illustrated my invention in the accompanying drawings, in which—

Figure 1 is a sectional view illustrating the plug inserted in the socket. Fig. 2 is a sectional view on line 2 2, Fig. 1.

Like letters refer to like parts in both figures.

The socket comprises a part *a*, having an opening through which the plug may be inserted and is also provided with a line-spring *b*, the end of which is arranged to engage a contact upon the plug and also carries a rigid or inflexible contact *c*. The plug comprises an insulating-sleeve *d* to serve as a handle, within which is arranged a metallic shell *d'*, the forward end of which in the present instance serves as a terminal of the plug and is adapted when the plug is inserted in the socket to rest within and make contact with the metallic part or sleeve *a*, having the opening for the reception of the plug. Within the metallic shell *d'* is an insulating-shell *d''*, and within the latter is a conducting-shell *d'''*, the outer end of which is enlarged to form the terminal *d''''*, with which the end of line-spring *b* is adapted to engage and make contact. Within the shell *d''''* is an insulating-body *d''''''*, through which passes a rod *d'''''''* of conducting material, the forward end of the rod extending beyond the body of insulating material

d''''''' and constituting a spring-terminal adapted to engage the rigid contact *c*. The end *d'''''''* of the rod *d'''''''* is enlarged and is adapted to engage a lateral extension *c'* on the rigid contact to insure the making of an effective contact and to hold the plug in place. A recess or opening *d''''''* is provided in the forward end of the insulating-body *d'''''''* to afford space to permit the lateral flexing of contact-rod *d'''''''*.

When the plug is inserted in the spring-jack, the engagement of the cylindrical portion of the plug with the opening through the part *a* serves to hold the plug in proper position and the line-spring *b* engages the terminal *d'''''''* of the plug, while the spring-tip *b'''''''* of the plug engages the rigid contact *c* of the spring-jack, the enlarged end of the spring-terminal and the lateral extension on the rigid contact serving to effectively hold the plug in position.

Having described my invention, what I claim as new, and desire to secure by Letters Patent, is—

1. In combination, a telephone switch-socket having an opening for the insertion of the plug and provided with a central rigid terminal and a spring-terminal at one side thereof, and a plug having a portion to rest within the socket-opening and carrying a central spring rod or terminal to engage the rigid switch-contact and an outer terminal to engage the spring-contact of the switch, substantially as described.

2. In combination, a telephone switch-socket having a spring-contact and a rigid central contact having a lateral extension on the end, and a plug having a contact to engage said spring-contact and a spring rod or terminal having a lateral extension on the end and adapted to engage said rigid contact, substantially as described.

In witness whereof I have hereunto subscribed my name in the presence of two witnesses.

WILLIAM W. DEAN.
